UNITED STATES PATENT OFFICE.

FRED W. MORGAN AND RUFUS WRIGHT, OF CHICAGO, ILLINOIS.

PNEUMATIC TIRE.

SPECIFICATION forming part of Letters Patent No. 502,047, dated July 25, 1893.

Application filed December 24, 1892. Serial No. 456,205. (No model.)

To all whom it may concern:

Be it known that we, FRED W. MORGAN and RUFUS WRIGHT, both citizens of the United States, residing in Chicago, in the county of Cook and State of Illinois, have invented a certain new and useful Improvement in Pneumatic Tires, of which the following is a specification.

Prominent objects of our invention are, to close the ends of the air-tube in a simple and reliable way; to permit the ready arrangement of the air-tube within a sheath having a limited opening; to likewise permit the ready removal of the air-tube from a sheath of the character aforesaid, and at the same time to so arrange the air tube within the sheath that notwithstanding its closed end portions it shall form a continuous air-cushion, which although capable of separation, will during service be practically held together as a single tube incapable of separation at the joint also to so close and arrange the ends of the air tube as to avoid strain and leakage at its said ends as a result of inflation and service. We may form the air-tube in any suitable way, although in practice we prefer to form it upon a mandrel, and to employ unvulcanized sheet-rubber as a material for the same. After forming the tube we flatten and close its end portions, either by rolling down the same or by pressure otherwise suitably applied, and then desirably vulcanize the tube so as to practically unite the meeting sides of each flattened end as one solid piece. The air-tube thus formed can then be drawn within an endless tubular sheath having a limited split or opening provided for the introduction of the air-tube, a ready way of drawing the tube within the sheath being to first tie to one end of the tube a string having at one end a weight, to then introduce said weight within the sheath by way of the limited opening in the latter, to then cause the weight to traverse the tubular passage within the sheath by properly moving the latter, and to then withdraw the weight and pull upon the string until the air-tube is completely threaded or drawn within the sheath. After thus introducing the air-tube within the sheath we lap the closed flat end portions of the air-tube upon the inflatable portions of said tube and after prefer-

ably placing a suitable layer of canvas or any suitable material between the air-tube and the split or opening in the sheath, we suitably close said split or opening. Whenever repair of the air-tube becomes necessary, the air tube can be deflated, the sheath opened, and the air-tube drawn out through the opening in the sheath, which said operation can be easily performed since the lapping end portions of the air-tube are separable from one another.

By flattening and closing the end portions of the air tube as aforesaid, we adapt them to withstand leakage under the strain of inflation, since in place of simply closing the tube at terminal points, we permanently unite its opposite walls along the end portions of the tube which union extends back some distance from the terminals of the structure, and render such flattened portions practically solid. This arrangement also permits us to lap the flattened end portions of the tube upon its inflatable portions which latter when inflated will clamp the flattened end portions against the inner wall of the sheath, thereby firmly holding them and avoiding any and all displacement during service, and effectively securing the tube against leakage.

In the accompanying drawings,—Figure 1 represents the air-tube prior to flattening its ends, a portion of the tube being broken away for convenience of illustration. Figs. 2 and 3 show the air-tube with its ends flattened. Fig. 4 is a longitudinal section through the air-tube with its flattened ends subject to compression by clips or clamps. Fig. 5 is a section through the sheath with the air-tube arranged therein and shown in elevation. Fig. 6 is a section through a portion of the tire. Fig. 7 shows said portion of the tire externally, and illustrates the split closed by lacing. Fig. 8 is a section taken transversely through one of the flattened end portions of the air tube as indicated by line $x-x$ in Fig. 3 and illustrates the line of meeting between the opposing flattened walls of the air-tube. Fig. 9 is a like view with the said line of meeting shown in Fig. 8 omitted in order to illustrate the practically solid condition of the flattened end portion when the same has been subjected to suitable pressure and to vulcanization.

The air-tube A, Fig. 1, can be formed in any suitable way and of any desired material but is preferably made of unvulcanized sheet-rubber. The ends of the tube can be flattened 5 as at *a* in any desired manner, such as by rolling down the same or by subjecting them to the pressure of clamping or pressing devices. When made of unvulcanized rubber it is preferably vulcanized after its ends have 10 been flattened, and in such case we have found it advantageous to subject its flattened ends to compression during vulcanization so as to insure perfect union. To such end therefore we have shown clips or clamps B 15 which can be employed to compress the flattened ends of the tube during vulcanization and which can be used in the first instance to thus flatten the tube ends. The flattened ends of the tubes will however unite by vul- 20 canization without such pressure, and hence we do not limit ourselves to the same. As another way, we can flatten the ends of the tube and unite the opposing flattened sides of its said ends by cement, and in fact we have 25 so made them with good results. Broadly considered therefore, we can flatten the ends by any suitable means, and unite the same by vulcanization, or by cementing, or by any mechanical device suitable for the purpose, 30 but as a matter of further and special improvement we flatten the ends of the tube and unite the same by vulcanization, and in such case we first construct the tube with unvul- 35 canized rubber which will unite by vulcanization, and by thus forming the air-tube, its flattened ends will be rendered solid and per- manently closed. The air-tube thus formed can then be placed within any suitable tire- sheath and the end portions of the tube can 40 be lapped so that unless the tube is inflated, it will in effect form a continuous tube, as illustrated in Figs. 5 and 6, wherein A indicates the air-tube arranged within a sheath C, and understood to be in an inflated condition. 45 By such arrangement the flattened ends *a* of the air-tube lap the inflatable end portions of the tube, and owing to their flattened condition occupy but little room and do not interfere with the inflation of the tire. Further 50 important advantages of such arrangement are that the tube can be readily and economically made, and that it can be easily introduced into a tubular sheath having only a short slit *c* as an opening through which ac- 55 cess can be had to the interior of the sheath.

We do not however for the broader purposes of our invention, herein limit ourselves to this particular construction of sheath which constitutes the subject of our application, Serial 60 No. 450,068, for Letters Patent of the United States, and may thus arrange the air tubes in any other suitable construction of sheath or casing; it being understood however, that for certain special purposes herein mentioned we 65 have in certain claims specifically included a tubular sheath having a limited slit or opening, in conjunction with certain other mat-

ters. The flattened terminals *a* of the air tube shown in said Figs. 5 and 6, lap to some extent the inflatable end portions of the tube, 70 and hence when the tube is inflated, the trans- versely flattened end portions of the tube will be pressed and firmly held against the inside wall of the sheath and when thus held against the transversely circular or curved inner wall of the sheath, the said flattened ends of the air- tube will be caused by the internal air pressure to partake of the transverse curvature of the wall of the sheath and thereby lie close to the same and occupy but very little space, it 80 being seen that the space occupied by the flattened end of the tube is simply proportional to the thickness of the said flattened end *a*, and hence the thinner the air tube, the thinner will be such flattened end. The tube 85 thus inflated will have the practical effect of a continuous tube since the abutting or op- posing lapping inflatable portions of the tube as at *a* will be pressed closely together by the confined body of air and will lie within the 90 sheath so as to form a flexible diagonally ar- ranged partition which will in no wise inter- fere with the general elasticity of the inflated 95 tire. Should repairs of the air tube become necessary, it can be deflated, and owing to the separability of the ends, it can easily be re- moved through an adjacent opening in the 100 sheath. In this relation the sheath having a short opening and the air tube having sepa- rately closed ends and arranged with its end 105 portions abutting against and lapping one an- other as shown, becomes a further special fea- 110 ture of improvement, it being obvious that an air tube having permanently joined ends could be thus removed through such opening 115 in the sheath, and that in order to remove a tube having permanently united ends, it 120 would become necessary to split the sheath along its entire length.

The hereinbefore described mode of flat- 125 tening the ends of the tube and vulcanizing the same so as to render said ends solid, forms a feature of improvement which is also pre- 130 ferably embodied in the foregoing described way of arranging the tube within the sheath, 135 although for the broader purposes of such ar- 140 rangement, we may flatten the ends of the tube and unite the opposing flattened sides of the same by cement or otherwise. Where the air tube is thus arranged within an endless 145 tubular sheath having a short split or suitable limited opening, we prefer arranging a pad 150 or layer D between the air tube and split or opening, which said pad or layer can be of any suitable material, either metallic, or fibrous 155 or the like.

What we claim as our invention is—

1. The within described improvement in forming inflatable tire tubes, consisting in flattening the end portions of the tube, and closing and uniting together the opposing flattened walls of the same as described.

2. The within described improvement in forming inflatable tire tubes, consisting in

flattening the end portions of an unvulcanized tube and vulcanizing the same with its flattened end portions subject to compression.

3. An inflatable tire tube having transversely flattened closed end portions, substantially as described.

4. An inflatable tire tube having flattened and solid closed end portions, substantially as described.

5. A hollow or pneumatic tire comprising an inflatable tube confined within a sheath and having closed transversely flattened end portions, substantially as described.

6. A hollow or pneumatic tire comprising an inflatable tube having flattened closed end portions, and confined within a sheath, the flattened end portions of said tube being arranged to overlap the inflatable portion of the tube, substantially as described.

7. A hollow or pneumatic tire comprising a tubular sheath having a limited split or

opening for the insertion and removal of an air tube, and an air tube having flattened end portions and confined within the sheath and having its flattened end portions removably held between the sheath and the inflatable portions of the air tube, substantially as set forth.

8. A hollow or pneumatic tire comprising a tubular sheath having a limited opening for the insertion and removal of the air tube, an air tube confined within the sheath and having flattened end portions, and a shield or layer arranged between the said opening and the inclosed air tube substantially as described.

FRED W. MORGAN.
RUFUS WRIGHT.
